(57) **CLAIM**

The ornamental design for a weight enclosure for an exercise machine, as shown and described.

DESCRIPTION

FIG. 1 is a perspective view of a weight enclosure for an exercise machine, showing my new design, wherein the broken line showing of the exerciser structure is for illustrative purposes only and forms no part of the claimed design;

FIG. 2 is a front elevational view of the weight enclosure for an exercise machine shown in FIG. 1;

FIG. 3 is a side elevational view of the weight enclosure for an exercise machine shown in FIG. 1.

FIG. 4 is a rear elevational view of the weight enclosure for an exercise machine shown in FIG. 1;

FIG. 5 is a top plan view of the weight enclosure for an exercise machine shown in FIG. 1; and,

FIG. 6 is a bottom plan view of the weight enclosure for an exercise machine shown in FIG. 1.
